UNITED STATES PATENT OFFICE.

FRANK EBERLE, OF NORFOLK, VIRGINIA.

DESIGN FOR A BADGE.

No. 38,428.

Specification for Design.

Patented Jan. 29, 1907.

Application filed November 7, 1906. Serial No. 342,425. Term of patent 3½ years.

To all whom it may concern:

Be it known that I, FRANK EBERLE, a citizen of the United States, residing at Norfolk, in the county of Norfolk and State of Virginia, have invented a certain new, original, and ornamental design for a Badge, reference being had to the accompanying drawing, which shows a plan view.

I claim—
The ornamental design for a badge as shown.

FRANK EBERLE.
